CHARLES M. YOUNG AND EMORY M. BENSTER, OF DETROIT, MICHIGAN.

Letters Patent No. 61,788, dated February 5, 1867.

IMPROVEMENT IN GAS STOVES.

The Schedule referred to in these Letters Patent and making part of the same.

TO ALL WHOM IT MAY CONCERN:

Be it known that we, CHARLES M. YOUNG and EMORY M. BENSTER, of Detroit, in the county of Wayne, and State of Michigan, have invented a new and improved Petroleum Gas Stove; and we do hereby declare that the following is a full, clear, and precise description thereof, which will enable others skilled in the art to make and use the same, reference being had to the accompanying drawing, forming part of this specification, in which—

Figure 1 represents a view in perspective of a petroleum gas stove with our improvements.

Figure 2 is a view from above, with the cover removed.

Figure 3, a section.

Figure 4, a view of our fire-cup detached.

Figure 5, a view of our combustion disk and improved generating chamber; and

Figure 6, three views of our combustion disk detached.

The nature of our invention consists in attaching to stoves intended to be heated with gas from petroleum, naphtha, or other inflammable fluids, a movable combustion disk, of the construction hereinafter shown, in connection with a generating chamber, of wrought iron or copper, instead of the stationary disk and cast-iron chamber heretofore used, for the purpose of doing away with the destructive heat communicated to the generating chamber by a disk, which forms part thereof, and also by the use of wrought-iron or copper pipe, diminishing the tendency to interior carbonization, which destroys the ordinary cast-iron chamber in a short time. Also in attaching to such stoves a fire-cup, of the construction shown hereinafter, and, in connection therewith, surrounding the gas flame with a fixed ring, for the purposes of saving the fluid which escapes during the process of lighting, and of concentrating the heat at the point required.

A represents a stove, which is of ordinary construction, except that the lower part is cast with an inner ring, A', which reaches to the top of the generating chamber D, except where it is cut away at o o, to admit of sliding the disk C towards the shut-off F. a is the upper part of the stove, made to slip on in the usual way; g, the cover; e, the rim on which the cover rests. L L¹ L² L³ are the legs. B represents what we call a fire-cup, which we make of cast iron, with a lip, d, and which is fastened to the stove A by the screw b, leaving the upper edge of the fire-cup sufficiently below the stove to admit a draught of air, as shown in fig. 3 of the drawing. The object of the fire-cup B is to receive the waste oil, which is kept from spreading over the stove by the fixed ring A', and drops into the recess at the bottom of the fire-cup, where it burns slowly away. C represents a movable combustion disk, which we make of cast iron, with a triangular projection, V, to part the flame, and keep it from the generator pipe D. The disk C has on its upper surface two loops, c c, which loosely fit the generating chamber D, so as to allow a circulation of air around the chamber, except at the point of actual contact. By means of the recess o o cut in the fixed ring A', the disk C may be moved from above the burner f for the purpose of lighting or cleansing. The object of the disk C is to distribute the gas flame evenly, and protect the generating chamber from the direct action of the flame. D represents the generating pipe and chamber, which we make in any of the known forms; but, instead of using cast iron, we make it of wrought iron or copper, either of which lasts much longer than cast iron without carbonizing, and which we are able to use in connection with the movable disk C, which protects the pipe from the severe heat, a hitherto unsurmountable objection to their use. E represents the reservoir, which we make of any known form; F, the stop-cock or shut-off, to regulate the supply of fluid; f, the burner; h, a support for the pipe D. The parts, except as hereinbefore described, we make in any of the usual forms, and, therefore, need no minute description.

The operation of lighting is performed by turning the stop-cock F so as to allow the fluid from E to escape at f, where it is ignited. After burning long enough to gasefy the fluid in the chamber D, the stop-cock is turned so as to supply the fluid in sufficient quantity to keep up with the consumption of gas.

Having thus described our invention, we claim as new, and desire to secure by Letters Patent—

1. The combination and arrangement of the fixed ring A' with the fire-cup B, for the purposes described.
2. The combination and arrangement of a movable combustion disk, C, with the wrought-iron or copper generating chamber D, substantially as and for the purposes set forth.
3. The movable combustion disk C, as described.
4. The fire-cup B, as described.
